UNITED STATES PATENT OFFICE

2,665,705

LOCOMOTIVE FRESH WATER SYSTEM

Robert Walsh, New York, N. Y., assignor to American Car and Foundry Company, New York, N. Y., a corporation of New Jersey

Original application September 2, 1949, Serial No. 113,727. Divided and this application December 29, 1950, Serial No. 203,490

3 Claims. (Cl. 137—208)

1

This invention relates to railway locomotives and more particularly to a fresh water supply system for trains and is a division of my application Serial No. 113,727 filed September 2, 1949.

It has been customary to provide coaches and berth type sleeping cars with self contained fresh water systems each consisting of a tank and connected faucet located in the aisle and/or washrooms. When the car is divided into rooms, an individual fresh water system is usually located in each room, but in any case the fresh water systems are individual to the car. Space in a passenger railroad car is limited and utilization of space for fresh water systems is objectionable. Further, the maintenance and servicing of systems individual to each car requires periodic attention and the labor cost for this purpose is objectionable.

An object of the invention is to overcome some of the objectionable features of fresh water systems now employed in railroad trains by arranging a common source of water supply in the locomotive where space is more available and accessibility for servicing is better.

Another object of the invention is to provide a fresh water system for a railroad train in which the supply reservoir is mounted in the locomotive and is maintained under pressure through connection with the main locomotive air pressure system.

Another object of the invention is to provide a fresh water supply system for a train in the rear end of the locomotive without interfering with a rear center aisle and in a manner to provide ample water storage.

These and other objects of the invention will be apparent to those skilled in the art from a study of the following description and accompanying drawings, in which:

Fig. 1 is an interior diagrammatic plan view of the rear end portion of a locomotive.

Fig. 2 is an interior diagrammatic side elevational view of the rear end portion of a locomotive.

Fig. 3 is a transverse sectional view of a locomotive looking toward the rear end and showing the fresh water system installation therein.

Fig. 4 is a view showing schematically the fresh water system in the locomotive.

Fig. 5 is a sectional view of one of the air and water control valves for the fresh water system shown in Fig. 4.

Fig. 6 is a perspective view of the control valve shown in Fig. 5.

Fig. 7 is a sectional view of the valve taken on line 7—7 of Fig. 5.

2

Referring now to the drawings by characters of reference, numeral 4 indicates generally a railroad locomotive of the type driven by internal combustion engines. The locomotive framing includes a center sill 6, side sills 8 and rear end sill 10. Angle members 34 are arranged above and welded to the side sills. Posts 42 are secured to the side and rear end sills and roof plates 40 are secured to the upper ends of the side sills. End plate 159 is secured to the end posts 42 and carlines 165 are secured to the roof side plates. A suitable cover 167 is secured over the roof and end framing. The rear supporting truck is indicated by numeral 356 and is provided with wheels 360 mounted on axle 358 that is driven by motor 362.

The reservoir portion of a fresh water system for a train is carried in the rear end of the locomotive. Two reservoir tanks 405 each have a lower flange 407 that rests on supporting flooring 409 at the rear of the framing and are secured thereon by bolts 410. Valve means is associated with each tank for controlling water supply and air pressure. Water inlet valve housing 412 has an outlet end that screws on an inlet pipe 414 leading to the interior of the tank. Within housing 412 is a spring closed valve 416 and a manually operated wobble valve 418 is arranged at the outside of the casing. Lever 420 is attached to the casing by pin 421 and valve 418 is mounted on pin 419 carried by the lever. Spring 422 normally acts on the lever to close the wobble valve. When valve 418 is manually opened, a water supply hose, from a source exterior of the locomotive, can be inserted into the inlet end of the housing and will hold valve 416 open during the filling operation. Water can be supplied to either inlet housing to fill both tanks as they are connected by an equalizer pipe 424. The tanks have a pressure blow off valve 426 so that air pressure in the tanks is maintained below a suitable maximum. Water outlet pipes 428 extend through the top of the tanks and are open adjacent the bottom of the tanks. Pipes 428 join with an outlet pipe 430 having a manually controlled valve 432 at its end to which a flexible pipe 434 is attached. Pipe 434 extends through the rear wall of the locomotive and has a coupling 436 at its end for attachment to a train line (not shown).

Air under pressure can enter the tanks through valve housings 438 attached to the water inlet housings 412. Inlet pipe 442 is connected with the inlet 441 of the valve housing and pipe 444 connects and is in series with the inlet of the other air valve housing with an outlet 443 of

the air valve housing. Pipe 446 and branch pipe 448 connect the second air valve housing with the upper portion of tanks 405. The air valve housings each have a vent pipe 450 attached to the outlet 445 opposite the outlet connection 443 with supply pipe 444. Two-way valves 452 in such housings 438 are rotatable by handles 454 to connect the air inlet pipe 442 with pipe 444 and pipe 444 with pipes 446 and 448 for allowing air flow to the pipes and this is the condition existing except when water is to be admitted to the tanks. Handles 454 are pinned to stems 455 held in the valve casings by nuts 457 above sealing members 465. The valves are secured to the stems by pins 461. The valves 452 when turned to cut off flow through pipes 444, 446, and 448, will connect supply pipes 442, 446, and 448 with vents 450 to thereby allow air to escape from the tanks and to cut off the supply of air. Gauges 456 indicate the height of water in the tanks and air pressure on the water in the tanks is maintained at approximately 100 lbs. pressure. When the air system is open to the tanks, cock flanges 463 on one side of the valve handles 454 will overlie and lock levers 420 to maintain valves 418 closed. But, when handles 454 are moved to release air pressure from the tanks, then their position is such that valves 418 can be opened. A pressure equalizer valve 458 is connected in supply pipe 459 to hold the air at the desired maximum pressure. Pipe 459 is suitably connected with the main locomotive compressed air system which includes compressor 460, mounted on support 462 secured to the rear portion of the locomotive flooring in advance of the tanks, driven by motor 464.

It will be noted that the tanks 405 are located at each side of the center aisle at the rear end of the locomotive leading to rear door 408. Thus, the tanks are out of the way and readily accessible for servicing. The rear door leads to steps 520 located above the rear coupling bar 516.

The invention may be modified in various respects as will occur to those skilled in the art and the exclusive use of all modifications as come within the scope of the appended claims is contemplated.

What is claimed is:

1. In a fresh water supply system for a railway train, a pair of water storage tanks mounted in a locomotive, water outlet pipes extending into the tanks and leading from the bottom central interior zone thereof, a train water supply line to which said outlet pipes are connected, a constantly open water level equalizer pipe extending only between and below the bottoms of said

tanks with its ends connected thereto, a water inlet connected with the upper portion of each tank, an air pressure inlet pipe connected with the tops of the tanks, two-way valves in series in the air pressure inlet pipe located one adjacent each tank, an air exhaust pipe open to the atmosphere connected with each of said two-way valves, and an air pressure supply pipe connected with one of said two-way valves, said valves each being operable to control the flow of air either to the tanks or from the tanks through the exhaust pipes to the atmosphere.

2. In a fresh water supply system for a railway train, a pair of water storage tanks mounted in a locomotive, water outlet pipes extending through the tops of the tanks and into the bottom central interior zone thereof, a train water supply line to which said outlet pipes are connected, a water inlet valve connected with each tank, an air pressure inlet pipe connected with the tops of said tanks, two-way valves in series in the air pressure inlet pipe located one adjacent each tank, a pipe connected with each two-way valve for exhausting air from the tanks to the atmosphere, and an air pressure supply line connected with one of the two-way valves, said two-way valves each being selectively operable to control the flow of air to the tanks or to vent air therefrom through said exhaust pipes to the atmosphere and shut off the air supply to the tanks.

3. In a fresh water supply system for a railway train, a water storage tank carried by the locomotive of the train, a water inlet valve for the tank, means acting to close said water inlet valve, a water outlet pipe extending through the top and leading from the bottom central interior portion of the tank, an air pressure system connected with the top of the tank, a two-way valve in the air pressure system having a handle operable to permit flow of air through the valve to the tank or to exhaust air therefrom through the valve to the atmosphere, and means on the handle of said two-way valve engageable with the closure means of said water inlet valve to lock the same in closed position when said two-way valve is turned by said handle to admit air into said tank.

ROBERT WALSH.
